MAGNETRON

Howard L. Steele, Jr., Bloomfield, and John W. McNall, East Orange, N. J., assignors to Westinghouse Electric Corporation, East Pittsburgh, Pa., a corporation of Pennsylvania

Application June 18, 1946, Serial No. 677,463

11 Claims. (Cl. 250—27.5)

1

This invention relates to magnetrons, and more particularly to the cathode structure thereof.

Electron discharge devices of the magnetron type are employed in the art for generating or sustaining electrical oscillations of very high frequency. Such devices usually contain an anode of generally cylindrical shape with an elongated electron emitting cathode axially sustained therein with both elements functioning in a vacuum.

It is found in the operation of magnetrons that after the cathode is raised to its normal or emissive temperature and copious emission prevails, that, without any alteration of the current to the heater filament, the cathode rises above normal temperature to its own detriment. Basically, since present-day magnetrons are only of the order of 50% efficiency, the cause for the increase in cathode temperature may be traced to the inefficiency of the magnetron. The explanation for this appears to be that a proportion of electrons emitted from the cathode are out of phase with the electromagnetic field, and are returned to the cathode after a more or less extensive excursion into the region between the cathode and anode. But during their sojourn in the electromagnetic field, those out-of-phase electrons absorb energy and when they return to the cathode, that energy is converted into heat at the cathode. Slight phase differences between the electrons and alternating current field between cathode and anode is permissible because such electrons usually get in step after a few convolutions. But with more than slight phase differences the electron usually returns to the cathode, and contributes to the inefficiency to the extent of energy absorbed in its excursion from the cathode and back again, which is translated into heat at the journey's end on the cathode. From the average low efficiency indicated above for magnetrons, it becomes apparent that a good portion of the energy imparted is converted to heat at the cathode, causing the cathode to operate at a temperature above normal therefor and shortening its life correspondingly.

The gravity of the heat exchange for efficiency is rendered more evident by the fact that, when the device is in normal operation, the developed heat is so intense that the external cathode heater power may be reduced sometimes even to zero and the device continues to operate as well as while the power was being applied. If, however, the anode voltage is interrupted for sufficient length of time, the bombardment of the cathode and emission stop and then to re-start the operation the cathode heater filament has to be used to again operate the cathode at the proper emissive temperature.

Bombardment results in the loss and destruction of the thermionically active material on the surface of the cathode. Also the higher temperature than normal for the cathode results in serious

2

evaporation of the active material, and in either event the active material lost from the cathode is in greater part found to be deposited on the inner concave face of the anode. This deposit on the anode interferes somewhat with the operating characteristics of the magnetron.

From its more general aspects, the invention has an objective of eliminating the defects referred to above and thereby increase the operating life and efficiency of the magnetron.

Another object is to provide an improved magnetron assembly and combination of parts.

More specifically, an object of the invention is to provide improved means for limiting and regulating the effective temperature of the cathode derived from electron bombardment.

A further object of the invention is to utilize the main cathode exclusively as a secondary emitter of electrons.

In conjunction with the last preceding object, the invention contemplates oscillation initiation from a source other than the main cathode.

The present concept includes provision of an auxiliary cathode as a primary emitter.

Important amongst the objects of the invention is inclusion of a primary emitter protected from runaway effect that would cause it to draw larger currents due to temperature increase.

Still further objects of the invention will appear to those skilled in the art to which the invention appertains as the description progresses, both by direct recitation thereof and by implication from the context.

Referring to the accompanying drawing in which like numerals of reference indicate similar parts throughout the several views;

Figure 1 is a vertical sectional view of a magnetron in accordance with the present invention;

Figure 2 is a cross-sectional view on line II—II of Fig. 1;

Figure 3 is a sectional view of the cathode similar to the showing thereof in Fig. 1, but on a larger scale; and

Figure 4 is a cross section on line IV—IV of Figure 3.

In the specific embodiment of the invention illustrated in said drawing, the reference numeral 10 designates a cylindrical magnetron body having end plates or covers 11 sealed thereto whereby the interior may be evacuated. The interior of said body is formed to comprise an anode 12 of generally cylindrical shape, shorter than the outside portion of the body which has end flanges 13 for spacing the covers 11 from the ends of the anode 12 and thereby affords the usual and necessary end spaces 14 within the magnetron. The present showing of anode provides a cathode cavity 15 coaxial with the magnetron body and anode and extending through the anode so as to open into both end spaces 14.

Amongst other details of the anode common to the prior art is provision therein of a plurality of resonant cavities 16 which radiate from the central or cathode cavity 15 and which likewise are open at their ends through the end faces of the anode into said end spaces. Intervening or partition walls 17 between the resonant cavities separate those cavities from each other and largely determine the size and shape of said cavities. The said radiating cavities constitute 10 cavity resonators and electrical coupling thereof is obtained by straps 18 here shown as rings at the ends of the anode and each of which connects different alternate walls 17 thereof.

Coaxially within the aforementioned cathode cavity 15 is a cylindrical secondary emission cathode 19. As shown, it is preferable that this cathode have its upper end lower than the plane of the upper end of the anode. Heating of this cathode, which for brevity will be distinguished as the main cathode, is derived from electron bombardment, and means are provided for limiting and regulating temperature of said cathode of optimum intensity for maximum efficiency as a secondary emitter but of insufficient intensity to cause any substantial primary emission. This heat control is shown accomplished by provision of a hollow within the cathode to and from which a fluid cooling medium is circulated by means exterior to the magnetron. Air, as well as water, oil and other liquids, are examples of cooling mediums which may be used. Circulation is obtained by provision of an entry or in-flow pipe 20 coaxially within an out-flow or discharge pipe 21. The discharge pipe extends well within the cathode coaxially thereof whereas the in-flow pipe 20 is shorter so as to accommodate fluid passage from the end thereof into the region exterior to the in-flow pipe but interior of the out-flow pipe. As a manufacturing expedient, the pipes are preferably assembled in proper terminal relation and the end of the outer pipe is then filled with a plug 22 after which the body material for the cathode is cast directly around the pipe. The portion of the pipe within the cast material, as well as plug 22, become unified with the cast material during the casting operation which affords a permanent rigid mounting for the cathode as well as high thermal conductivity for heat exchange purposes. The secondary emitter or main cathode 19 may be of suitable material for the purpose, of which silver-magnesium is preferred; beryllium-copper alloy is another suitable material; and other examples may be given of copper bases on which a coating is applied, for instance a coating of sprayed aluminum.

It is to be particularly noted that the coaxial pipes 20, 21, project from what will be termed the lower end of the main cathode and into the end space 14 thereat, and that the said lower end of the cathode is substantially in a common plane with the lower end of the anode. Below said plane, coaxial to said pipes and securely held on the outer of said pipes by solder or otherwise, is a heavy metal disc 23 general term for which in the art, is "hat." Said hat is of greater diameter than the main cathode and preferably at least equal to the diameter of the cathode cavity of the anode. The function of the hat in the prior art has been to confine the electrons from escape at the end of the cathode cavity. In practice, however, especially when the magnetron is used for continuous wave operation, the hat has suffered from electron bombardment, has become heated very considerably 75

and has been an undesired source of electron emission. According to the present invention, the hat is not only made of metal which is non-magnetic and a good heat conductor, such as copper or molybdenum, but is of greater thickness and mass than those used in the prior art and is given the best possible contact with the pipe 21, so that, by conduction to said pipe, the hat is kept below temperature at which it would be emissive of electrons.

The principal feature of the present invention is exemplified by the structure at the upper end of the anode in upper end space 14. As there shown, an auxiliary cathode 24 is provided opposite the upper end of the main cathode 19 in coaxial alinement therewith but spaced therefrom. Preferably the two cathodes are of approximately the same diameter, but it is desirable to have the auxiliary cathode of slightly smaller diameter than the main cathode in order to avoid evaporation difficulties. Furthermore, the auxiliary cathode is of a character which is copiously emissive of thermionic electrons. By preference, and as illustrated, the auxiliary cathode 24 is a coil of wire which is emissive material throughout or some metal coated with emissive material such as strontium or barium oxide, or which is otherwise rendered copiously emissive. The coil constitutes a thermionic cathode and accordingly is constructed with appropriate electrical resistance so it can be heated by flow of current therethrough, for which purpose it is in electrical continuity with lead-in wires 25 which are introduced from the exterior radially through the end flanges 13 of the magnetron body into the end space 14. Appropriate seal and insulation for these lead-in wires 25 is provided, one form of which may be seen in Fig. 2 as comprising a hollow nipple 26 sealed to the magnetron body and having a sleeve 27 sealed at its outer end and 40 which in turn is sealed to a glass cap 28 through which the wire passes in sealed contact.

Auxiliary emissive cathode 24 is mounted within a recess in hat 29 which is of inverted cup shape so that its end wall is most remote from and opposite the end of the secondary emissive or main cathode. Said end wall of hat 29 has holes therein for passage of the ends of the auxiliary cathode therethrough, insulators 30 being provided in the holes for electrically isolating the said ends from the hat. This hat 29, by virtue of its cup shape, is furthermore provided with a peripheral wall or skirt 31 which depends from the end wall of the hat toward the anode and girdles the auxiliary cathode, said skirt preferably being as deep as the auxiliary cathode so the latter is contained entirely within the recess of the hat. The end of the hat 29 toward the main cathode and anode preferably has an outer diameter substantially as great as 60 the diameter of the cathode cavity 15 and thus, like the cap 23 at the opposite end of the anode, functions to deter escape of electrons into the end space 14. Enclosure of the auxiliary cathode 24 within hat 29 in conjunction with potentials employed and magnetic field from the usual magnets, not shown, for the magnetron, virtually constitutes the hat 29 and auxiliary cathode 24 an electron gun from which emitted electrons pass 65 into the cathode cavity 15. Said hat 29 is preferably non-magnetic and a good heat conductor of high melting point, such as molybdenum.

A further feature of the present invention is provision of means for cooling the auxiliary cathode hat or "gun." This is accomplished by means

quite similar to that described above for cooling the main cathode. In greater detail, said means comprises inner and outer coaxial pipes 32, 33 which are respectively employed as inlet and outlet for a cooling medium or fluid such as air, water or oil. The outer or outlet pipe 33 has its inner end secured in a radially disposed hole in said cap 29 preferably in the region of the end wall of said cap. Since the cap is preferably molybdenum, a copper solder or braze may be employed to secure the pipe tightly in the cap. The said outlet pipe 33 projects radially through the flange 13 of the magnetron body and through a nipple 34 sealed to said flange but with the pipe out of contact from either the flange or nipple. At the outer end of the nipple is a sleeve 35 sealed thereto and of metal capable of sealing to one end of a glass collar 36 the other end of which is sealed to a similar sleeve 37 which in turn is sealed to a metallic head 38. Pipe 33 extends from the cap 29 through the nipple 34, sleeves 35, 37 and collar 36 to said head 38 and opens at its end into a lateral passage 39 from which a discharge pipe 40 projects for carrying off fluid from the outlet pipe 33. A suitable choke 41 is provided on outlet pipe 33 to prevent flow of radio frequency current from the magnetron by that path.

Inner or inlet pipe 32 has its inner end or end toward the cap 29 inset from the end of the outer pipe 33 thereby permitting fluid flow from the end of the inner pipe into the end region of the outlet pipe and then back to the discharge outlet through the space between the outer surface of the inner pipe and the inner surface of the outer pipe. The other or outer end of the inner pipe 32 passes through the aforementioned lateral passage 39 beyond the end of the outer pipe and is sealed in said head and in communication with a supply pipe 42. The structure thus described, therefore provides for cooling medium flow to the cap 29, prevents radio frequency loss, and yet provides for applying desired direct current potential to the hat. The electrical connection for applying the direct current potential may be made to head 38 by virtue of metallic pipe connection 33 from the head to the hat which will act as an electrical conductor and support insulated from the magnetron body. Use of a more positive potential on the hat will increase primary emission from auxiliary cathode 24 and permit utilization of a lower emitter temperature and heating power. As it is desired to utilize the electrons in the cathode cavity, and as positive potential on the hat tends to attract the electrons thereto, the potential on the hat is kept as least positive as possible, or even negative.

Without repeating the description in detail, but by duplicating essential reference numerals on the drawing, it will be clear that the inlet and outlet insulated mounting for the cooling medium pipes 20, 21 for the main cathode is like that for the "gun" and that the outlet pipe for the cathode constitutes an electrical connection for application of desired potential to the said cathode.

In review of the advantageous results obtained by the present invention, it must be emphasized that magnetron operation on direct current rather than on pulsed voltage has the difficult problem of cathode overheating, and that even at 1000:1 duty cycle, it is common experience for pulsed thermionic cathodes to maintain an emission temperature, or higher, from back bombardment alone, but on continuous wave operation such heating becomes definitely prohibitive except at very much lower powers. Maintenance

of high power, however, with continuous wave operation is essential for a commercially practical magnetron. Solution of the problem therefore not only includes cooling of the main cathode, but also provides for that cathode to be copiously emissive of secondary electrons. However, a cathode of that characteristic necessitates introduction of means for starting it with a source of thermionic current, in other words, requires inclusion of an emitter of primary electrons. The invention, therefore, also solves this problem and overcomes shortening of the life of both the primary and secondary emitters and provides a magnetron wherein stable operation can be maintained.

It will be understood that the problems to be solved are more severe for magnetrons used on continuous wave operation than on pulsed operation. However, in either use, it appears quite preferable to utilize a main cathode and an auxiliary cathode which are substantially both of the same general shape, cylindrical as shown, and which are of approximately the same diameters. For either use, it has been found satisfactory for production of radio frequency, to situate the cathode emissive of primary electrons about an eighth inch from the plane of the end of the anode for a magnetron having approximately a 10 cm. wavelength output. However, with such close spacing, the auxiliary cathode is insufficiently remote from the anode to prevent excessive heating on continuous wave operation from back bombardment. The problem thereby introduced has been solved by the "gun" construction of auxiliary cathode with cooling of the hat forming part thereof. Electrical isolation of the cathodes enables desired potential to be applied to each for regulation of effective emission.

We claim:

1. A magnetron comprising an evacuated enclosing housing having an anode therein, said anode providing a cathode cavity longitudinally central thereof, a cathode coaxial of and within said cavity and emission from which is substantially secondary electrons only, and means at one end of said cathode for conducting a cooling medium both to and from said cathode.

2. A magnetron comprising an evacuated enclosing housing having an anode therein, said anode providing a cathode cavity longitudinally central thereof, a main cathode coaxial of and within said cavity and emission from which is substantially secondary electrons only, means at one end of said cathode for conducting a cooling medium both to and from said cathode, and an auxiliary cathode at the opposite end of said main cathode from said means.

3. A magnetron comprising an evacuated enclosing housing having an anode therein, a main cathode in said anode, an auxiliary cathode emissive of primary electrons opposite an end of said main cathode, means around said auxiliary cathode for confining the region peripherally around said auxiliary cathode, and means connected with and for conducting a cooling medium both to and from said confining means.

4. A magnetron comprising an evacuated enclosing housing having an anode therein, said anode providing a cathode cavity longitudinally central thereof, a main cathode coaxial of and within said cavity emission from which is substantially secondary electrons only, an auxiliary cathode at an end of said main cathode, said auxiliary cathode being emissive of primary electrons,

7 and means proximate to and for cooling both of said cathodes.

5. A magnetron comprising an evacuated enclosing housing having an anode therein, said anode providing a cathode cavity longitudinally central thereof, a main cathode coaxial of and within said cavity emission from which is substantially secondary electrons only, an auxiliary cathode at an end of said main cathode, said auxiliary cathode being emissive of primary electrons, means around said auxiliary cathode for confining the region peripherally around said auxiliary cathode, and means connected with and for conducting cooling medium both to and from said confining means and to and from the main cathode.

6. A magnetron comprising an evacuated enclosing housing having an anode therein, said anode providing a cathode cavity longitudinally central thereof, a cathode coaxial of and within said cavity emission from which is substantially secondary electrons only, and means proximate to and for conducting a cooling means to and from said cathode, said conducting means comprising pipes one within another of which the inner pipe opens at its end within the outer pipe and of which the outer diameter of the inner pipe is less than the inner diameter of the outer pipe for effecting flow passage from one pipe to the other and between said pipes.

7. A magnetron comprising an evacuated enclosing housing having an anode therein, a main cathode in said anode, an auxiliary cathode emissive of primary electrons opposite an end of said main cathode, means around said auxiliary cathode for confining the region peripherally around said auxiliary cathode, and means proximate to and for conducting a cooling medium both to and from said confining means, said conducting means comprising pipes one within another of which the inner pipe opens at its end next said confining means within the outer pipe and of which the outer diameter of the inner pipe is less than the inner diameter of the outer pipe for effecting flow passage from one pipe to the other and between said pipes.

8. A magnetron comprising an evacuated enclosing housing having an anode therein, said anode providing a cathode cavity longitudinally central of the anode opening at opposite ends thereof, a cathode in said cathode cavity, hats opposite and in proximity to the open ends of said cathode cavity, and means connected with

10 and for conducting cooling fluid to and effective upon each of said hats for cooling the same.

9. A magnetron comprising an evacuated enclosing housing having an anode therein, said anode providing a cathode cavity longitudinally central of the anode opening at opposite ends thereof, a main cathode in said cathode cavity, hats opposite and in proximity to the open ends of said cathode cavity, one of said hats having a recess directed toward and on a common axis with the cathode cavity, and an auxiliary cathode in said recess, said cathodes both being cylindrical on a common axis and substantially equal in diameter.

15. 10. A magnetron comprising an evacuated enclosing housing having an anode therein, said anode providing a cathode cavity longitudinally central of the anode opening at opposite ends thereof, a main cathode in said cathode cavity, hats opposite and in proximity to the open ends of said cathode cavity, one of said hats having a recess directed toward and on a common axis with the cathode cavity, an auxiliary cathode in said recess, and means connected with and for conducting cooling fluid to said recessed hat.

20 11. A magnetron comprising an evacuated enclosing housing having an anode therein, said anode providing a cathode cavity longitudinally central of the anode opening at opposite ends thereof, a main cathode in said cathode cavity, hats opposite and in proximity to the ends of said cathode cavity, one of said hats having a recess directed toward and on a common axis with the cathode cavity, an auxiliary cathode in said recess, means connected with and for conducting cooling fluid to said recessed hat, and means connected with and for conducting cooling fluid into said main cathode at the end thereof remote from said recessed hat and through the other of said hats.
